UNITED STATES PATENT OFFICE.

LEE G. EARL, OF JACKSONVILLE, FLORIDA.

METALLIC TIE.

1,105,325.

Specification of Letters Patent. Patented July 28, 1914.

Application filed May 6, 1913, Serial No. 765,890. Renewed June 18, 1914. Serial No. 845,981.

To all whom it may concern:

Be it known that I, LEE G. EARL, a citizen of the United States, residing at Jacksonville, in the county of Duval and State of Florida, have invented certain new and useful Improvements in Metallic Ties, of which the following is a specification.

This invention relates to ties and more particularly to a metallic tie which will 10 eliminate the use of spikes, splice bars or other analogous fastening means and which at the same time will prevent the creeping of the rail upon the tie which has very often been due to the fact that the spikes have 15 been withdrawn from the ties, due to the pressure exerted upon the rail.

An object of this invention is the provision of a tie which will automatically lock the rail therein and from which the rail may 20 be readily extracted when it is so desired.

A further object of this invention is the provision of a tie which is provided with pivoted ends so as to facilitate the insertion and extraction of the rail with respect to the 25 tie and means for making said ends stationary by simple and efficient means which will be more fully hereinafter described.

Other objects as well as the nature, characteristic features and scope of my invention 30 will be more readily understood from the following description taken in connection with the accompanying drawings and pointed out in the claims forming a part of this specification.

35 Referring to the drawings: Figure 1 is a side elevation of my improved tie showing the rails in place thereon; Fig. 2 is a top plan view of the same; Fig. 3 is a detail enlarged perspective view of one of the ends; 40 Fig. 4 is a detail enlarged perspective view of a portion of the tie proper; Fig. 5 is a side elevation of a portion of the tie showing the end thereof swung downwardly and in a position to receive the rail; and Fig. 6 is a 45 top plan view of the rail showing a notch in one of the base flanges thereof.

It has been well known in this art to provide metallic ties which have the opposite ends thereof pivoted so as to facilitate the 50 insertion and extraction of the rail with respect to the tie, without providing means for preventing the rail from coming out of the tie due to the ballast or earth on which the tie has been laid, being washed away by 55 the flow of water or the like which is very often the case, thereby allowing the ends to

swing downwardly in the arc of a circle so as to allow the rails to be readily extracted from the tie when pressure is exerted thereon, and it is the object of this invention to 60 not only provide a tie in which the rail may be readily inserted or extracted but likewise to provide a device in which the rail after having been inserted will be prevented from either transverse or lateral movement due to 65 a peculiar formation of the tie which has been made to overcome objections heretofore appearing in devices of this character.

In the drawings wherein is shown the preferred form of my invention, the numeral 70 10 indicates the tie proper which may be made of any suitable metal and has the opposite ends thereof reduced so as to form arms 11, the said arms extending upwardly through the transverse recessed portion 22 of 75 the rail so as to form a shoulder 13 which is shown to advantage in Fig. 4. The arms 11 are provided with openings 14 and 14^a, the function of which will be more fully herein-after described. A longitudinal slot or 80 opening 15 is formed in the tie which not only reduces the weight thereof but likewise provides an opening into which is inserted ballast or the like which will positively lock 85 the tie from movement in any direction, the tie being further provided with transversely arranged studs 16 on the base thereof which likewise prevent movement of the tie and especially eliminates the lateral movement thereof. 90

Ends 17 are provided, each of which has a recess 18 which conforms to the curvature of the arms 11 and is adapted for the reception of the same, being pivotally mounted thereon through the medium of a bolt 19 or a 95 similar pivotal means which extends through the opening 14 and is provided not only in the arms but likewise in the ends 17 which is shown to advantage in Fig. 3. The ends 17 are further provided with transversely extending recesses 20 which are adapted for the reception of one side of the base flange of the rail, the other side extending through the transverse recess 12 in the tie proper. In Fig. 6 is shown a rail 21 which has a 100 notch 22 therein, the said notch being adapted for engagement with the shoulder 13 which is provided by extending the arms 11 upwardly through the recess 12 and thereby eliminates the transverse movement of the 110 rail on the tie.

After the rail has been inserted in the tie,

the second opening 14^a has been provided in the ends 17 and the arms 11 so that a bolt 23 or a similar means may be passed therethrough thereby holding the said ends in a stationary position so as to eliminate the danger of the rail jumping out of the tie when undue pressure is exerted thereon especially in going around curves where the flange of the wheel comes in contact with the side of the rail and has a tendency to force the same outwardly on the tie if means have not been provided to insure the anti-creeping of the rail.

In the construction of a railroad of this type, the tie would be first laid on the ballast and the rail then placed thereon which would be done by hoisting the tie upwardly through the medium of a jack or any suitable hoisting means so as to allow the pivoted ends thereof to swing downwardly as shown to advantage in Fig. 5. As soon as the rail has been placed on the tie, the base flanges of the rail which come in contact with the inner ends 24 of the pivoted member 17 will swing said ends 17 upwardly into a horizontal position due to the pressure of the rail, thereby automatically locking the same in the tie. When it is desired to move the rail from the tie, the tie is hoisted so as to allow the pivoted end 17 thereof to move in a downward direction and the rail is readily extracted therefrom. As before stated, after the rail has been inserted in the tie, the bolts 23 are passed through the openings 14 which will rigidly engage the end 17 with the tie proper 10. Ballast is then placed in the slot or opening 15 of the tie which, as before stated, is for the purpose of preventing the movement thereof.

It will be understood that the above description and accompanying drawings comprehend only the general and preferred embodiment of my invention and that various minor changes in details of construction, proportion and arrangement of the parts may be made within the scope of the appended claims and without sacrificing any of the advantages of my invention.

Having thus fully described my invention, what I claim as new and desire to secure by Letters Patent is:

1. A metallic tie including a plurality of sections, the intermediate of said sections being provided with an arm on each end thereof, the said intermediate section being provided with a transverse recess in each end thereof, the said arm having a portion thereof extending upwardly and bisecting said transverse recess, the ends of said tie being adapted for pivotal engagement upon said arms, said ends being provided with transverse recesses on the inner ends thereof, the recesses in said intermediate portion alining with the recesses in said ends whereby to provide a seat for the base flange of a

rail and means for preventing the movement of said ends.

2. A metallic tie including a plurality of sections, the intermediate of said sections being provided with a longitudinal slot therein, arms formed by reducing the ends thereof, the said intermediate portion being further provided with transverse recesses on the opposite ends thereof, shoulders extending upwardly from said arms and adapted to bisect the recesses, the recesses of said intermediate portion alining with recesses in the end portions adapted for the reception of the base flange of a rail, said shoulders extending through said base flange so as to prevent the longitudinal movement thereof.

3. A metallic tie comprising a plurality of sections, the intermediate of said sections being provided with a longitudinal slot therein adapted for the reception of materials for preventing the movement of said tie, arms formed on the opposite ends of said intermediate section, said intermediate section being further provided with recesses in the opposite ends thereof, shoulders extending upwardly and bisecting said recesses, the end portions of said tie being pivotally mounted on said arms and provided with transverse recesses on the inner ends thereof, the recesses of said intermediate portion alining with the recesses of said end portions and adapted to receive the base flange of a rail therein, said shoulders adapted for engagement with said base flange for preventing the movement thereof and a bolt carried by said ends and said arms for holding said ends in a fixed position.

4. A device of the character described including a plurality of pivotally connected solid sections the intermediate of which is provided with an elongated longitudinally extending slot, a multiplicity of studs arranged on the base of said tie, said elongated section having each end thereof reduced so as to provide arms each of which is adapted for engagement beneath a rail, the end sections of said tie engaging said rail for holding the same on said arms, and bolts extending through said ends and said arms, for holding the former, at times, in a fixed position.

5. A device of the character described including a plurality of pivotally connected solid sections the intermediate of which is provided with an elongated longitudinally extending slot, a multiplicity of uniformly spaced apart transversely extending studs arranged on the base of said intermediate section, each end of said elongated section being reduced so as to provide an arm for engagement beneath the base flange of a rail, said opposite ends having portions thereof cut out above said arms in which the one side of said base flange engages, the pivoted ends of said tie having a portion

thereof cut out so as to provide a bifurcated end, the branches of the bifurcation engaging with the arms of said elongated section, a bolt for pivotally engaging each of said ends with said elongated section, and a bolt extending through the branches of said bifurcated end and subjacent the expanding recesses of said elongated section and said

ends for holding the latter, at times, in a fixed position.

In testimony whereof I affix my signature in presence of two witnesses.
